United States Patent Office

Des. 226,370
Patented Feb. 27, 1973

226,370

BOTTLE OR SIMILAR ARTICLE

Michael D. Cromb, Shrewsbury, N.J., assignor to Midland Glass Company, Inc., Cliffwood, N.J.

Filed May 10, 1971, Ser. No. 142,085

Term of patent 14 years

Int. Cl. D9—01

U.S. Cl. D9—1

FIG. 1

FIG. 2

FIG. 1 is an elevational view of a bottle or similar article showing my new design, the opposite side being substantially the same in appearance as the side shown; and

FIG. 2 is a top plan view thereof.

I claim:

The ornamental design for a bottle or similar article, substantially as shown and described.
